(57) CLAIM

The ornamental design for a light therapy headband, as shown and described.

DESCRIPTION

FIG. 1 illustrates a top perspective view of a light therapy headband;

FIG. 2 illustrates a front view of the light therapy headband thereof;

FIG. 3 illustrates a back view of the light therapy headband thereof;

FIG. 4 illustrates a left side view of the light therapy headband thereof;

FIG. 5 illustrates a right side view of the light therapy headband thereof;

FIG. 6 illustrates a top view of the light therapy headband thereof;

FIG. 7 illustrates a bottom view of the light therapy headband thereof; and,

FIG. 8 illustrates a back perspective view of the light therapy headband thereof.

The broken lines shown in the drawings are for purpose of illustrating portions of the light therapy headband, which form no part of the claimed design.
